UNITED STATES PATENT OFFICE

2,058,380

PERMANENT WAVE HEATER

Lawrence Edward Knospe, Chicago, Ill.

Application February 19, 1936, Serial No. 64,769

3 Claims. (Cl. 219—24)

This invention relates to electrically operated hair curlers of the type in which the lock of hair to be curled is wound upon a curling rod serving as a core and therewith placed in an electrical heater.

Hitherto it has been customary in the curling of hair to wind a small wisp of the hair around a suitable curling rod, impregnate this hair with permanent wave liquid, cover the wisp of hair with pads impregnated with the liquid and enclose the core with the wisp of hair and pad for a short period of time in an electrically operated heater.

The use of pads is objectionable, expensive and time-consuming. Therefore, it is an object of the present invention to provide an electrically operated hair curler which will eliminate the use of pads.

The treatment of hair upon the human scalp requires great care to prevent accidents and failure as well as the possibility of burning the scalp and hair.

A further object of the invention is, therefore, to provide an electrically operated hair curler in which the heater is provided with thin sheets of asbestos cloth upon the inner exposed faces of both the lower and the upper heater sections to positively eliminate the possibility of injury to the hair or scalp.

Usually also the curling rods have merely consisted of a spindle tapering from the ends to a slender central portion about which the lock of hair is wrapped to be enclosed in the heater. The disadvantage of this is that ends of the hair protrude, and considerable time is consumed to wrap the hair properly.

A further object of the invention is, therefore, to provide a spindle having a hinged finger which latter not only holds the lock of hair in position during and after the wrapping operation but which is also provided with an absorbent layer of material which may be saturated with the permanent wave fluid, the finger being perforated to permit the fluid to impregnate the wrapped lock of hair and thus during the heating operation produce a better shaped curl, in less time than has hitherto been possible.

Attempts have hitherto been made to reduce the weight and bulk of electrically operated curling heaters while retaining the necessary rigidity of the parts. However, devices of this character are still uncomfortable and far too cumbersome.

It is therefore, a still further object of the invention to provide a light strong and durable device of this character which may be applied

close to the scalp without danger of burning the latter, and which will be inexpensive to manufacture and will require minimum time of the operator to apply and remove from the hair.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of the specification,

Figure 1 is a longitudinal sectional view of the hair curler showing the upper section of the heater open and showing the curling rod in applied position.

Figure 2 is a side elevation of the electrically operated hair curler shown in Figure 1 and showing the electrical plug connected therewith.

Figure 3 is a plan view of the parts shown in Figure 2 with the plug removed and showing the roller rocked open to permit application of the device to the hair at the scalp.

Figure 4 is a cross sectional view through the upper section of the heater.

Fig. 5 is a cross sectional view through the lower section of the heater.

Figure 6 is a left end elevation of the parts shown in Figure 2.

Figure 7 is a cross sectional view taken on the line 7—7 of Figure 2 looking in the direction of the arrows and with the plug connector removed.

Figure 8 is a detail perspective view of the curling rod and showing the hinged finger thereof open.

Figure 9 is an enlarged cross sectional view through the curling rod with the finger closed and showing a lock of hair wrapped on the curling rod.

Figure 10 is a detail sectional view showing the ratchet end of the curling rod.

Figure 11 is a cross sectional view taken on the line 11—11 of Figure 10.

Figure 12 is a side elevation of the key and smoothing pin.

Referring now to the drawings in which like characters of reference designate similar parts in the various views, 10 designates a base which may be formed of any suitable light strong material such as "Bakelite". The base is provided with a substantially square extension 11 at one end, as shown in Figure 5. A roller 12 covered with a rubber cylinder 13, as shown in Figure 7, is hinged

to one corner of the extension 11, as shown in Figure 3. For this purpose the roller is provided with a hinge ear 14 which enters a kerf 15 in the extension and a pivot pin 16 is passed through the extension, kerf, and through the ear to pivotally mount the parts.

When the roller is open, as shown by dotted lines in Figure 3, the device may be applied to the lock of hair close to the scalp with the roller 10 against the scalp so that the device will be comfortable to the wearer. The roller is held closed by means of a latch 17 which is pivoted at one end in a kerf 18 in the base by means of a pivot pin 19 passed through the kerf and latch. The 15 latch is bifurcated at the end, as shown at 20, in Figure 6, to receive an axial screw 21 on the free end of the roller. A nut 22 on the screw may be tightened against the bifurcated end of the latch to hold the roller in the closed position, as shown 20 in Figure 3.

The heater, as best shown in Figure 7, comprises upper and lower sections 23 and 24, the upper section being convex and the lower section being concave downwardly. Each section is 25 formed of light strong metal defining an interior space for the reception of the resistance coils. The ends of the resistance coil 25 of the lower section are conducted through the extension 15 to two pins 26, as shown best in Figures 1 and 5. 30 The resistance coil 27 of the upper section has its ends conducted to a pair of metal eyes 28 which are carried by and insulated from a metal casing 29 projecting from one end of the upper section, as also shown best in Figures 1 and 4. 35 The lower section 24 of the heater is secured stationary to the base by means of a screw 30 at one end of the section, and also by the above mentioned screw 19 which forms a pivot for the latch 17. A hinge tongue 31 rises from one end of the 40 lower section and is reduced and bent outwardly at its upper end, as best shown in Figure 5 to engage in an eye 32 on the outer end of the upper section, as best shown in Figure 4. The lower heater section and upper heater section are both 45 hinged together by the tongue 31 and eye 32 but the upper section 27 may be detached from the lower section by simply withdrawing the eye 32 from the tongue 31.

For locking the hinged upper section 27 closed 50 against the lower section the casing 29 is provided with a slot 33 which receives a pin 34, as shown in Figure 2, the pin being hinged at the lower end by means of a screw 35 on the base 10. A nut 36 on the screw may be tightened against 55 the casing 29 to hold the upper section of the heater closed.

The upper section 23 is provided on the lower surface with an insulating facing 37 and the upper surface of the lower section is likewise provided with an insulating facing 38. These facings may be formed of thin sheet asbestos composition, and the ends of the facings pass over the longitudinal edges of both heater sections and embrace said edges, as best shown in Figure 7. 60 Consequently the confronting surfaces of both sections of the heater are insulated so that when the sections of the heater are closed to heat the lock of hair wrapped on the curling rod, no metal can touch the hair.

By lining the sections of the heater with insulating material the usual pads now in general use in connection with hair curlers are positively eliminated. Only the insulating facings 37 and 38 70 can touch the hair and these facings can in no

manner burn or otherwise damage the hair during the heating operation.

By now referring to Figures 8 and 9 it will be seen that the curling rod 39 is tapered from the ends toward center and at both ends is provided with rectangular lugs 40, either of which may be interchangeably received in an opening 41 in the tongue to support the curling rod non-rotatably between the sections of the heater, as shown in Figure 1.

10 The curling rod is provided with a finger 42 which is provided at one end with hinge ears 43 through which and one end of the spindle, a pivot pin 44 is passed to hingedly secure the finger to the curling rod.

15 As best shown in Figure 9 the finger 42 is formed of three thicknesses, including an outer shell 45 of metal, an inner shell 46 of metal, and an intermediate lining 47 of absorbent material, which may be saturated with the permanent wave fluid. 20 The finger is provided with perforations 48 through which the fluid may escape and permeate the lock of hair wound on the curling rod.

25 In operation the hair is first moistened with permanent wave fluid and then a lock of the hair may be wound upon the curling rod 39. To facilitate winding the hair upon the curling rod one of the lugs 40 is provided with a resilient dog 49, as best shown in Figure 11, which engages ratchet teeth 50 in the counterbore end of the curling 30 rod and permits rotation of the rod in one direction when the lug is engaged in the rectangular opening of the tongue 31. A key 51 is used to rotate the curling rod, the key having a rectangular recess 52 which forms a socket wrench to 35 receive the other lug 40 of the curling rod. The key is provided with a reduced axial pin 53 which forms a smoothing pin to work stray ends around the curling rod when winding hair.

40 After the inner layer of the finger is saturated with permanent wave fluid the finger may be closed upon the wrapped curl and will hold the curl firmly in shape without any short ends protruding. Now the curling rod with the wrapped hair thereupon may be placed between the 45 opened sections of the heater with one squared end 40 of the curling rod engaged in the similar shaped opening 41 in the heater. The upper section 27 of the heater may now be closed to engage the eyes 32 with the pins 26.

50 The device may now be applied to the head by opening the roller 13 to the dotted line position shown in Figure 3, and closing the roller to grip the hair close to the scalp. A plug connector 49 may now be applied to the pins 26 to supply current to the resistance coils of the sections of the heater.

55 While the finger 42 in Figure 7 is shown as of a single thickness this showing is merely diagrammatic, the detail construction being illustrated 60 in Figures 8 and 9.

From the above description it will be seen that the invention includes a heater having two sections, the confronting inner faces of which are lined with insulating material so that no metal 65 can touch the hair and that in use this heater will positively eliminate the use of permanent wave pads since the heater is applied directly to the hair after the hair has been moistened with the permanent wave fluid. Elimination of these 70 pads results in the saving of the operator's time in the permanent waving process and also results in a saving of money as no permanent wave pads need be bought with the machine.

75 It will also be seen that since no metal can 75

touch the hair danger of burning the hair is also positively eliminated.

From the above description it is thought that the construction and operation of the invention will be fully understood without further explanation.

What is claimed is:

1. A hair curler comprising a heater having a pair of hollow sections hinged together, one of the sections being concave and the other being convex downwardly, facings of asbestos cloth covering the inner surfaces of the sections and embracing the longitudinal edges thereof, resistance coils in the sections, and means for connecting the resistance coils to a source of electricity when the sections are closed.

2. A hair curler comprising a heater having a base of insulating material, a rubber covered roller hinged at one end to said base for clamping the base to the hair at the scalp, means for locking the roller closed, upper and lower heating sections, one of which is concave and the other convex downwardly, means securing one of said sections to the base, a detachable hinge connection between said sections, means for locking the sections closed, heating coils carried by the sec-

tions, means for electrically connecting the heating coils to a source of electricity when the sections are closed, facings of insulating material on the confronting inner faces of the sections, and a curling rod adapted to be received between said insulating facings.

3. A hair curler comprising a heater having mating heating sections hingedly connected together, a base of insulating material supporting one of said sections, said sections being adapted to receive a curling rod therebetween, one of said sections being concave and the other of said sections being convex downwardly, each section being hollow, a resistance coil in the hollow of each section, electric terminals carried by the base and connected to the coil of one section, insulated terminal eyes connected to the coil of the other section and adapted to receive and be electrically connected to said terminals when the sections are closed, means for locking the sections closed, and insulating facings of asbestos cloth on the confronting surfaces of the sections and extending over and embracing the longitudinal edges of the sections.
